UNITED STATES PATENT OFFICE.

WILLIAM F. MILLER, OF MIAMI, FLORIDA, ASSIGNOR TO RELLIM INVESTMENT COMPANY, INC., OF MIAMI, FLORIDA.

SEPTIC TANK.

Application filed June 25, 1928. Serial No. 288,211.

This invention relates to septic tanks which are used for the disposal of sewage in communities which do not have a modern sewage disposal system, the primary object being to 5 construct a tank from precast units of such form that a tank of any desired capacity may be easily produced. Another object of the invention is to produce units of novel form which may be quickly assembled into 10 a tank and united in such a manner that the joint will be effectually sealed and will not open and leak as the tank settles. Other objects will appear in the course of the following description and the invention resides in 15 certain novel features which will be particularly pointed out in the appended claims.

In the accompanying drawings;

Figure 1 is a plan view of a tank of three units constructed in accordance with the invention, the top being omitted and parts being in section;

Figure 2 is a central longitudinal section of the same;

Figures 3, 4 and 5 are perspective views 25 of the different tank units shown in Figs. 1 and 2.

The drawings show three typical units 1, 2 and 3, the units 1 and 2 being end units and the unit 3 being an intermediate unit. The 30 units are formed of concrete or cementitious material in suitable molds and each unit is preferably of a generally cylindrical formation. Referring particularly to the unit 1, it will be noted that in the wall thereof, near 35 its top, there is an inlet opening 4 in which the end of a drain pipe from a building may be received and secured, and on the inside of the wall over and around said opening is a baffle tube 5 by which the inflowing sewage is 40 retarded so as to avoid disturbing the bacteria which flows on the surface of the stream. At a point preferably diametrically opposite the baffle 5, an opening 6 extends through the wall of the unit and an offset or flange 7 is 45 formed on the exterior of the unit around said opening, said flange extending the full height of the unit. In the side walls and bottom of the opening 6 is a continuous 50 groove 8, the ends of which open through the top of the offset as shown at 9, the walls of the opening 6 being preferably flared outwardly. The unit 2 has an outlet opening 10 and a baffle tube 11 in form and location corresponding to inlet 4 and baffle 5, and also 55 has an opening 12 with an external flange or

projection 13 extending around the same, the opening 12, however, being smaller than the opening 6 and the flange 13 being tapered or beveled so that it readily enters the opening 6 without causing chipping of either flange. 60 On the sides and bottom of the flange is an external groove 14 which mates with the groove 8 when the parts are assembled, grout, plaster or the like being poured through the openings 9 to completely fill the mating 65 grooves 8 and 14 and form a key binding the units together and sealing the joint. In order that the builder may be advised that a perfect waterproof seal is formed and that there are no air pockets to hold back the 70 sealing mix, a hole 15 is formed in the floor or bottom of the opening 12 which hole communicates with the groove 14. When the compound is poured through the opening 9, the workman can see it coming out at the 75 hole 15 and he will then know that there is a perfect seal of the units which will be strong and waterproof when the mix sets in the grooves.

The unit 2 is provided with vertically disposed grooves 16 which receive a baffle plate 17 terminating short of the floor or bottom of the unit and serving to retain the sewage in the sludge chamber provided by the units and permit only the purified water to pass 80 to and escape through the outlet 10.

In many cases, the two end units will provide a tank of sufficient capacity, but if a larger tank is desired, the intermediate unit 3 is employed and as many intermediate units 90 may be used as may be necessary to meet the requirements. The intermediate unit is without baffle tubes, such as 5 and 11, and is formed with openings 18, 19 corresponding, respectively, with the opening 12 of the unit 95 2 and the opening 6 of the unit 1. Around the opening 18 is an external flange 20 corresponding in all respects to the flange 13 of the unit 2 and around the opening 19 is an external flange 21 corresponding in all respects to the flange 7 of the unit 1. When the intermediate unit is to be used, the flange 20 thereof is fitted in the opening 6 of the unit 1 and the flange 13 of the unit is fitted in the opening 19 of the intermediate unit, 100 the flanges being keyed and sealed in the manner previously described. If more than one intermediate unit is to be used, the flange 20 of one unit is fitted in the opening 19 of another unit so that there is formed a long 105 110

sluge chamber in which the bacteria is held to act upon the sewerage so that to purify the liquid content which will pass under the baffle plate 17 and escape through the outlet 5 of the end unit 2. After all the units have been assembled and united, a flat cover may be placed over the top completing the tank.

By my invention a tank of any desired size may be easily and quickly built and the several units will be so effectually united that, except under some very abnormal conditions, sinking of the ground will not cause opening of the joints.

Having fully described my invention what I claim as new and desire to secure by Letters Patent, is:—

1. A precast open-top unit for septic tanks having an opening through its wall and extending substantially the full height of the same and provided exteriorly with a flange around said opening, the sides and bottom of the flange having a continuous groove in their outer sides, the ends of which open through the top of the flange and the top of the flange 25 having a continuous uninterrupted surface to fit closely within a mating unit to aid in supporting the same and prevent relative turning thereof.

2. A septic tank consisting of precast open-top units arranged side by side and each having an opening through its wall and an external flange around the opening, the flange on one unit mating with and fitting within the flange on the adjacent unit, the flanges having registering grooves in their opposed lateral surfaces to receive a sealing and bonding composition and the outer flange having openings through its top portion alined with the ends of the grooves, and a cover extending over all the units and resting on the upper edges thereof and on the top portions of the outer flanges.

3. A septic tank consisting of precast units arranged side by side and each having an opening through its wall and an external flange around the opening, the flange on one unit mating with and fitting within the flange on the adjacent unit, the flanges having registering grooves in their opposed surfaces to receive a sealing and bonding composition, the inner flange having a sight hole formed in its floor communicating with said grooves.

In testimony whereof, I have signed this specification.

WILLIAM F. MILLER.
